UNITED STATES PATENT OFFICE.

EMIL TYDEN, OF EVANSTON, ILLINOIS.

SEAL LOCKING DEVICE.

Application filed March 23, 1921. Serial No. 454,758.

To all whom it may concern:

Be it known that I, EMIL TYDEN, a citizen of the United States, and resident of Evanston, in the county of Cook and State of Illinois, have invented certain new and useful Improvements in Seal Locking Devices, of which the following is a specification, reference being had to the accompanying drawings, forming a part thereof.

10 The purpose of this invention is to provide an improved means for sealing a securing device, the same being shown embodied in a bag tie securing device or lock, but not being limited to such embodiment.

15 It consists in the elements and features of construction shown and described as indicated in the claims.

In the drawings:

20 Figure 1 is a perspective view of a bag tie securing device equipped with this invention.

Figure 2 is a longitudinal section, as at the line, 2—2, on Figure 1.

25 Figure 3 is a section at the line, 3—3, on Figure 2.

Figure 4 is a perspective view of the sealing strip employed as part of the complete sealing device as shown in the other figure.

30 In respect to this construction for securing the bag tie, the device shown in the drawings is substantially identical with the bag tie securing device which is the subject of my co-pending application, Serial No. 435,404, filed January 6, 1921, and a brief description of this structure will suffice here.

The tie securing device consists of a base member and a latch B, pivoted to the base for swinging into engagement with a hood, 40 B¹, on the latter, at the opposite end of the base from that at which the latch is pivoted thereto, and a cord gripper, C, lodged in the base adjacent the hood end of the latter, the base having at that end cord apertures, a and b, and the gripper having notches, c, c, positioned for riding on the cord at points inward from the cord apertures, a and b, the latch and hood having co-operating cam features for causing the latch to clamp the

45 gripper onto the cord when the latch end is forced under the hood. The hood has in its outer end wall a seal aperture, a², for a sealing strip, E; and the latch at the end which enters the hood has a seal catch chamber, 50 B², in whose opposite end walls are formed seal apertures, b² and b³, which at the cord-

clamping position of the latch,—that is when it is fully entered under the hood,—are aligned with the seal aperture, a². The sealing strip, E, is made of sheet material, 60 preferably metal, as commercial tin, though other material such as celluloid may be used. It consists of a straight narrow strip having its width reduced over a portion of its length from one end back to shoulders, e¹, 65 e¹, the full width part, E², from said shoulders toward the other end being of a width to enter the seal catch chamber, B², through the aperture, b², and emerge through the aperture, b³. The narrower part, E¹, of the sealing strip is of a width to pass through the aperture, a², which is too narrow to admit the wider part, E², of the sealing strip. Said wider part of the sealing strip has struck from opposite lateral marginal portions two spring fingers, E³, E⁴, which are sprung out of the plane of the strip at opposite directions, as seen in Figure 2. The distance of the free ends of the spring fingers from the shoulders, e¹, e¹, is less than 70 the distance from the inner side of the apertured end wall of the hood to the inner side of the opposite end wall of the seal catch chamber by an amount at least as great as the thickness of said apertured end 75 wall of the hood. The sealing strip is extended beyond the free end of the spring catch fingers, E³, for a length sufficient to cause it to protrude outside the seal catch chamber as seen in Figure 1, far enough to 80 be grasped by the fingers of the operator for manipulating the seal as hereinafter explained. The narrower part, E¹, of the sealing strip is weakened to facilitate its breaking and to insure its breaking at the proper 85 point by an aperture, e⁴, a distance from the shoulders, E³, substantially the amount of the thickness of the apertured end wall of the hood, so that the sealing strip may be readily broken by an authorized person 90 bending it back and forth at the point at which it emerges from the hood.

The operation of the device may be understood from the foregoing description to be as follows:

105 The latch being swung into cord-securing position under the hood, the sealing strip is inserted, narrow end first, through the aperture, b², into said end on through the seal catch chamber, passing through the aperture, b³, and then through the aperture, a², 110 in the forward wall of the hood; the protrud-

ing end being grasped by the operator, will be pulled through until the spring catch fingers—sprung back into the plane of the strip in order to pass through the aperture, b^2 , are entered fully into the spring catch chamber and spring out into engagement with said wall; and at this position the shoulder, e^1 , of the sealing strip preventing the strip from passing through the aperture, a^2 , said sealing strip is securely held by engagement with the spring catch chamber and prevents the latch from being swung aside from under the hood. When an unauthorized person breaks the seal at the weakened point just outside the hood as above explained, the oppositely protruding end of the strip may be grasped by the operator and the strip pulled back to withdraw the severed end out of engagement with the aperture, a^2 , of the hood, and thereupon the latch may be swung aside, releasing the cord from the gripper. The operator may now thrust the remnant of the seal out of the seal catch chamber by pushing on the end which protrudes out through the aperture, b^2 , and the device is then ready for re-latching and sealing.

I claim:—

1. In combination with a permanent securing device designed to be sealed in locked position and having for that purpose a seal catch chamber; having apertures in two opposite walls for a sealing strip to be inserted entirely through the chamber, and a sealing strip adapted to be so inserted, and adapted to be ruptured outside the catch chamber at the side thereof through which it is entered, the casing and the strip having co-operating a spring finger and a catch shoulder adapted for engagement against withdrawal from the strip in the direction from which it enters the chamber.

2. In the construction defined in claim 1 foregoing, two spring fingers oblique to the plane of the strip at opposite sides thereof each adapted for co-operation in the same direction with an engaging shoulder.

3. In a permanent securing device designed to be sealed in locked position, in combination with two parts pivoted together for turning relatively to effect securement, one of said parts having a seal-catch chamber and the other having a hood into which said chamber is entered at securing position of said two parts; the seal-catch chamber in the hood having apertures which are aligned at said securing position for the insertion of a sealing strip through the chamber and the hood, a sealing strip adapted to be so inserted the strip and the chamber having co-operating a spring finger and a catch shoulder adapted for engagement against withdrawal of the strip in the direction from which it enters the chamber.

4. In a permanent securing device designed to be sealed in locked position, com-

bination with two parts pivoted together for turning relatively to effect a securement, one of said parts having a seal-catch chamber and the other having a hood into which said chamber is entered at securing position of said two parts, the chamber and the hood having apertures aligned at securing position for the insertion of a sealing strip through the chamber; a sealing strip adapted to be so inserted having a shoulder at which it is widened beyond the dimension of the hood aperture, whereby it is prevented from being drawn entirely through the chamber, and being weakened for breaking at a transverse line at a distance beyond the shoulder at least equal to the thickness of the apertured wall of the hood; co-operating means on the strip and the chamber wall for preventing the withdrawal of the strip in the direction from which it enters the chamber, said means being relatively positioned on the strip and chamber wall to permit the reversed or withdrawing movement of the strip equal to the distance from the shoulder to the breaking line of the strip.

5. In combination with a permanent securing device designed to be sealed in locked position, in combination with two parts pivoted together for turning relatively to effect a securement, one of said parts having a seal-catch chamber and the other having a hood into which said chamber is entered at securing position of said two parts; the seal-catch chamber and the hood having apertures which are aligned at said securing position for the insertion of a sealing strip through the chamber and the hood; a sealing strip having spring catch fingers normally sprung out of the plane of the strip and adapted to yield back toward said plate for entering through the seal apertures of said chamber; the strip being weakened for breaking at a transverse line at a distance back from the end of said spring fingers less than the distance from the outer side of the hood to the inner side of the remote end of the chamber by an amount at least as great as the thickness of the apertured wall of the hood.

6. In the construction defined in claim 1 foregoing, the spring fingers being formed by striking the material in opposite directions from the plane of the strip along opposite edges of said strip.

7. In the construction defined in claim 1, foregoing, the spring strip being reduced in width at a portion of its length, the portion which is engaged in the seal-catch chamber being unreduced forming shoulders facing in the direction of the reduced portion, the seal aperture of the hood being narrower than the unreduced portion of the seal and adapted to admit the reduced portion, whereby the shoulders are stopped against the apertured end of the hood; the seal aper-

ture in the adjacent end of the chamber being of the full unreduced width of the seal strip.

8. In the construction defined in claim 1 foregoing, the sealing strip being reduced in width at a portion of its length, the portion which is engaged in the seal-catch chamber being unreduced, the shoulders facing in the direction of the reduced portion, the seal 10 aperture of the hood being narrower than the unreduced portion of the seal and adapted to admit the reduced portion, whereby the shoulders are stopped against the apertured end of the hood; the seal aperture in the

adjacent end of the chamber being of the 15 full unreduced width of the seal strip, said seal strip being extended in length beyond the spring fingers for projecting out through the opposite end of the seal aperture of the chamber and thereby accessible for retracting 20 the seal after rupture to bring the severed end within the hood and for thrusting the seal remnant out of the chamber.

In testimony whereof, I have hereunto set my hand at Chicago, Illinois, this 21st day 25 of March, 1921.

EMIL TYDEN.
